UNITED STATES PATENT OFFICE.

WILLIAM W. H. SNELL, OF NEW YORK, N. Y.

BOAT-LAUNCHING DEVICE.

1,295,626.

Specification of Letters Patent.

Patented Feb. 25, 1919.

Application filed August 22, 1918. Serial No. 251,019.

To all whom it may concern:

Be it known that I, WILLIAM W. H. SNELL, a citizen of Finland, (but having declared my intention to become a citizen of the United States,) residing at New York, in the county of New York and State of New York, have invented certain new and useful Improvements in Boat-Launching Devices, of which the following is a specification.

This invention has relation to launching devices for life boats, and has for an object to provide means particularly designed to safely launch a life boat from the high side of a listing vessel and to prevent injury to the life boat ordinarily resulting from the impact of the life boat against the side of the vessel in a heavy sea.

Another object of the invention is to provide a launching means which includes guide ways secured to the hull of the vessel exteriorly thereof and extending substantially vertically, and means attachable to the life boat to ride in the guides during descent of the life boat causing the latter to hug the side of the hull until the life boat reaches the water level.

A still further object of the invention is to provide resilient means forming the attachment between the life boat and vessel to cushion or prevent shocks that may result from movements of the life boat toward and away from the hull during the rocking motion of the latter.

In addition to the foregoing this invention comprehends improvements in the details of the construction and arrangement of parts to be hereinafter set forth and particularly pointed out in the appended claims.

In the accompanying drawings in which similar and corresponding parts are designated by the same characters of reference throughout the several views in which they appear—

Figure 1 is a view in perspective of a listing vessel illustrating the manner in which life boats are launched by means of my invention.

Fig. 2 is a view in plan of a life boat and my invention attached thereto.

Fig. 3 is a detail view illustrating one manner of forming the resilient connection.

Fig. 4 is a similar view taken at right-angles to the former view.

Fig. 5 is a detail view of a modified form of connection, and

Fig. 6 is a detail view of a device for connecting the spring to the attaching plank.

With reference to the drawings, 10 indicates the hull of a vessel, and 11 guide ways which extend vertical of the hull on the exterior face thereof and are arranged in pairs, one pair for each life boat to be launched. Each guide way consists of a pair of plates 12 arranged in parallelism and secured by rivets at their remote edges to the hull, while their adjacent edges are bent away from the hull to form a recess or guide way.

To each life boat there is secured a plank 13 to extend longitudinally of the life boat. The plank may be attached by means of a cable or cables 14 secured to the ends of the plank and wrapped around the boat.

An additional securing means may be provided in the way of angular members or hooks 15 pivoted to the gunwales of the boat and adapted to engage the plank. To the outer face of the plank at each end there is secured an annular member 16 having its central portion bent out of the plane of the balance of the member to form an annular pocket in which to receive an end convolution of a coiled spring 17. Secured to the other end of the spring is a cylindrical block 18 having an annular groove 19 in which to receive one of the convolutions of the spring. The block 18 is formed with an extension 20 to enter the space between the plates of one of the guide ways, and oppositely extending arms 21 are formed on the extension to extend at right angles thereto and to be housed in the recess of the guide way. Each arm 21 is formed with a transverse aperture to receive a hard steel ball 22, forming an anti-friction means to facilitate movement of the parts just described along the guide ways. It will be obvious that many other arrangements may be devised to slidably engage the ends of the springs in the guide ways, as for instance in Fig. 5 wherein 23 indicates a bolt having a spherical head 24 formed either rigidly or loosely at one end. The other end of the bolt loosely enters a central opening in a block 18^a forming the equivalent of the block 18.

In use the life boats are lowered from the deck of the listing vessel by means of the

conventional davits and block and tackle. The plank 13 and appurtenant parts having been already attached to the life boat, the arm 21 supplied with the ball bearings, or 5 the spherical heads 23 as the case may be are inserted in the guide ways and the boats lowered. It will be obvious that movement of the life boat toward or away from the hull of the vessel will be limited and shocks 10 due to impact cushioned, thereby preventing injury to the life boats and insuring the arrival of the latter at the water's edge intact with its load. The lower ends of the guide ways it will be noted terminate at a point adjacent 15 the water line of the vessel so that the life boat will be automatically released when reaching the water level.

While I have illustrated and described my invention with some degree of particularity I realize that in practice various alterations therein may be made. I therefore reserve the right and privilege of changing the form of the details of construction or otherwise altering the arrangement of the 20 correlated parts, without departing from the spirit of the invention or the scope of the appended claims.

Having thus described my invention, what I claim as new and desire to secure by 25 United States Letters Patent, is:

1. In combination with the hull of a vessel, guide ways on the vessel, and resilient means for attachment to a life boat and to ride in the guide ways.

2. In combination with the hull of a vessel, guide ways on the vessel, a support for attachment to a life boat, resilient members secured to the support, and means for engaging the resilient members in the guide ways.

3. In combination with the hull of a vessel, a pair of guide ways on the vessel, a support for attachment to a life boat, a pair of coiled springs attached at one end to the support, and anti-friction means on the other end of each spring for engagement in 45 the guide ways.

4. In combination with the hull of a vessel, a pair of guide ways on the vessel, a support for attachment to a life boat, a pair of coiled springs attached at one end to the support, a T-shaped member secured to the other end of each spring to engage in the 50 guide ways, and spherical anti-friction member held in the T-shaped member to facilitate movement of the latter along the guide 55 ways.

5. In a life boat launching apparatus a support for attachment to a life boat, a coiled spring attached at one end thereto, a block inserted in the other end of the 60 spring, oppositely extending arms on said block having their ends apertured, and spherical member held in said apertures, said arms and spherical members being designed to ride in guide ways on a vessel side. 65

In testimony whereof I affix my signature.

WILLIAM W. H. SNELL.
